WALL AND CEILING COVERING.

No.19,619.

Patented Jan. 28, 1890.

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,619, dated January 28, 1890.

Application filed December 26, 1889. Serial No. 335,050. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming a part thereof.

5 The leading feature of my design consists of a center ornamented with a bold continuous scroll 1, with volutes 2 and 3, ornamented with leaves, seeds, and flowers. There are 10 large ornaments of fruit 4 and flowers 5 and 6.

15 The design has an upper and lower narrow

border 7 and 8, similar in pattern, consisting of continuous rows of buttons or flower-blooms and a plain beading.

What I claim is—

The design for a wall and ceiling covering 20 herein shown and described, consisting of a continuous scroll ornamented with flowers, seeds, and fruit, and forming volutes, and having an upper and lower border ornamented in a continuous row of buttons or flower- 25 blooms and a plain beading.

PAUL GROEBER.
